UNITED STATES PATENT OFFICE.

HARRY D. ELLIOTT, OF BEVERLY, MASSACHUSETTS, ASSIGNOR TO UNITED SHOE MACHINERY CORPORATION, OF PATERSON, NEW JERSEY, A CORPORATION OF NEW JERSEY.

SOLE-PRESSING MACHINE.

Application filed November 4, 1919. Serial No. 335,624.

To all whom it may concern:

Be it known that I, HARRY D. ELLIOTT, a citizen of the United States, residing at Beverly, in the county of Essex and State of Massachusetts, have invented certain new and useful Improvements in Sole-Pressing Machines; and I do hereby declare the following to be a full, clear, and exact description of the invention, such as will enable others skilled in the art to which it appertains to make and use the same.

The present invention relates to sole pressing machines and more particularly to the type of sole pressing machines which are known in the art as sole laying machines.

In sole laying machines as now commonly constructed a relative movement of approach is imparted to the shoe supporting jack and the sole pressing pad, by means of a treadle actuated mechanism, to cause the sole to be engaged between the shoe and pad, and thereafter a relative sole pressing movement is imparted to the jack and pad by power actuated mechanism thrown into operation by the operator. One advantage of a machine of this construction is that a predetermined pressure may be applied on the sole irrespective of the thickness thereof or the height of the shoe, or, in another aspect of the matter, that the pressure action of the machine is regulated or controlled by the thickness of the work. The treadle actuated mechanism of these machines, however, puts considerable work on the operator and also renders the machines somewhat slow in operation.

An object of the present invention is to produce a novel and improved sole laying machine which in addition to having the advantage above described of said prior machines, is provided with power operated mechanism for imparting to the jack and pad both relative movements of approach and sole pressing movements.

With this and other objects in view, the features of the invention comprise certain constructions, arrangements and combinations of parts hereinafter described and claimed, the advantages of which will be obvious to those skilled in the art.

The several features of the invention will be clearly understood from the following description and accompanying drawings in which:

Figure 1 is a front elevation, partly in

section, of a sole laying machine embodying the features in their preferred form; Fig. 2 is a left side elevation of the machine; Fig. 3 is a plan view of the lower portion of the machine; Fig. 4 is a sectional view taken on the line 4—4 of Fig. 2; Figs. 5, 6 and 7 are detailed plan, front and side elevations, respectively, of one of the shoe supporting jacks and the upper portion of its operating mechanism; Fig. 7^a is a sectional detail of the jack guiding mechanism taken on the line 7^a—7^a of Fig. 6; Fig. 8 is a view similar to a portion of Fig. 2 on an enlarged scale; Fig. 9 is a detailed longitudinal sectional view of a portion of the driving mechanism of the machine; and Fig. 10 is a sectional view taken on the line 10—10 of Fig. 9.

The present invention is illustrated in the drawings as embodied in a machine arranged with twin presses to lay the soles on right and left shoes respectively, the sole being laid on one shoe by one press while the work is being changed on the other press. Each press comprises a sole laying pad 2 and a shoe supporting jack 4 positioned beneath the sole laying pad. In the operation of the machine a jack is raised by power operated means to position the sole of a shoe placed on the jack in light contact with the associated sole pressing pad and then the jack is raised a predetermined distance to apply pressure to the sole. The operation of the machine in this manner results in a predetermined pressure being applied on the sole irrespective of the thickness thereof or the height of the shoe. When one jack is being thus raised to lay the sole, the other jack is being retracted from its pad and at the completion of the retracting movement, the jack is automatically tilted forwardly and the machine is automatically brought to rest. The forward positioning of the jack upon stopping the machine permits the work to be readily and conveniently changed. When it is desired to again start the machine into operation, the operator returns the retracted jack to its operative position beneath the pad which automatically throws into operation the mechanism for raising the retracted jack as described and for retracting the other jack to repeat the cycle of operations.

The sole laying pads are held against the pressure of the jacks by means of thrust

springs and there is provision in the machine for independently adjusting these springs which thereby varies the amount of pressure applied on the soles. There is also provision in the machine for adjustment of the pads simultaneously toward and from the jacks.

Each sole pressing pad is mounted on the under side of a carrier 6 which in turn is pivotally mounted in a yoke formed at the lower end of a vertical slide 8, the upper end of which slide is cylindrical and is guided by a bearing 10 in a cross-head 12 hereinafter described. The upper portion of the slide 8 is provided with an axial aperture 14 the lower end of which is reduced to form an annular shoulder 16. The slide is held in the bearing 10 by means of a bolt 18 which extends through the axial aperture 14 and the lower end of which is provided with a collar or head 20 which engages the under side of the annular shoulder 16. The upper end of the bolt 18 extends through a central aperture in a cap 22 secured to the upper end of the bearing 10 and on the end of the bolt 18, adjacent the upper side of the cap 22, is secured a hand wheel 24 by which the bolt may be turned. A nut 26 is threaded on the bolt 18 adjacent the under side of the cap 22 which nut is mounted to permit the bolt to run through it but is held from turning by means of a key 28 projecting therefrom which engages vertical slots 29 in the slide 8 and the bearing 10. The pad is urged downwardly to resist the pressure of the jack by means of a spring 30 coiled about the bolt 18 and interposed between the annular shoulder 16 and the nut 26. By adjusting the tension of this spring through the hand wheel, the pressure applied on the work by means of the pad and jack may be varied and this adjustment may be readily effected by means of the hand wheel 24. The cross-head 12 upon which both pads are mounted is supported at its ends by vertical standards 32 which extend through apertures in the ends of the cross-head and the cross-head is clamped at its ends to the standards by means of suitable clamping devices 34. The cross-head is centrally supported by means of a vertical rod 36, the lower end of which is secured to the frame of the machine and the upper end of which is threaded through a sleeve 38 which in turn is journaled in a vertical bearing 39 in the cross-head. The sleeve 38 is held from longitudinal movement in its bearing by means of a collar 40 secured to its upper end and by a hand wheel 42 secured to its lower end engaging the ends of the bearing 39. With this construction, the sole pressing pads may be adjusted toward and from the jacks by first releasing the clamping devices 34 and then turning the hand wheel 42.

Each shoe supporting jack is mounted on a carrier 46 which in turn is mounted to slide

on a cross-head 48. The jack comprises a heel post 50 and a toe rest 52 mounted upon a horizontal bar 54 secured to the upper end of the carrier, the heel post and toe rest having the usual provision for adjustment toward and from each other to accommodate lasts of different sizes. The carrier is guided on the cross-head by means of an upright post or stud 56 secured to the cross-head which is received by a bearing 58 in the carrier. The initial movement of the jack to position the shoe sole in light contact with the pad is imparted from a driving member of the machine through yielding connections with the carrier. At the completion of this movement, the jack is held in position to retain the sole in contact with the pad by means of a locking device comprising a pawl and ratchet which locks the carrier to the cross-head. The sole pressing movement is also automatic and is imparted to the jack by mechanism comprising a toggle connected to the cross-head and actuated by the main driving shaft of the machine.

The mechanism for imparting the initial movement to the jack comprises a pair of cam segments 60 located beneath the carrier which, when swung upwardly, act to raise the carrier by engagement with a pair of rolls 62 loosely mounted on a horizontal shaft 64 secured to the carrier. The shaft 64 extends through transverse apertures in the bearing 58 and through a slot 66 in the guiding stud 56, the slot 66 being elongated in order that the shaft 64 may not interfere with the movement of the carrier on the cross-head. The locking device for locking the carrier to the cross-head at the completion of the initial movement of the jack comprises a ratchet member 68 secured to one side of the outer one of the cam segments 60, which ratchet member is engaged by a spring pressed pawl 70 pivoted at 72 on the cross-head. The cam segments 60 are secured to a horizontal shaft 74 which extends through an aperture in the stud 56 and has its ends journaled in bearings in the cross-head. The shaft 74 is rocked to swing the cam segments 60 upwardly by means of an arm 76 which forms an extension of one of the cam segments. The arm 76 is swung upwardly to thus actuate the cam segments by mechanism actuated by an oscillating shaft 78 journaled in bearings in the base of the machine. The shaft 78 is continuously oscillated by means of a cam 80 formed on the hub of a driving pulley 82 loosely mounted upon the driving shaft 84 of the machine, through a cam roll 86 mounted on the upper end of a lever 88 fulcrumed on the base of the machine, which lever is connected at its upper end by a link 90 with an arm 92 secured to one end of the shaft 78, the cam roll being maintained in engagement with the cam by means

of a spring 98 acting on a horizontal arm 94 of the lever 88. The connections between the rock shaft 78 and the cam segment actuating arm 76 comprise a rod 96 having its upper end pivotally connected to the arm 76 and its lower end extending through a sliding sleeve 98 pivotally mounted on the outer end of an arm 100 which is loosely mounted on the rock shaft 78. Means are provided so that when it is desired to impart the initial movement to the jack, the arm 100 will be connected to the rock shaft 78 in such manner that upon movement of the rock shaft in a counter-clockwise direction, Fig. 8, the arm 100 will be swung upwardly therewith which, through the sliding sleeve 98 and a spring 102 coiled about the rod 96 will yieldingly raise the arm 76, the spring 102 being interposed between a collar 104 secured to the rod 96 and a collar 106 loosely mounted to slide on the rod and adapted to be engaged by the sleeve 98. The means for thus connecting the arm 100 to the rock shaft 78 comprises a pawl 108 pivoted on the arm 100 and acted upon by a leaf spring 110 which engages a tail piece 112 projecting from the upper end of the pawl. The lower end of the pawl is normally maintained out of engagement with the rock shaft 78 against the action of the spring 110 by the engagement of the tail piece 112 with the rear end of a lever 114 pivoted at 116 on the base of the machine. At the proper time the lever 114 is disengaged from the tail piece of the pawl, allowing the end of the pawl to be swung against the rock shaft 78, so that upon the next movement of the rock shaft in a counter-clockwise direction, (Fig. 8), a notch 118 therein will engage the end of the pawl and carry the arm 100 upwardly therewith. Upon the return movement of the rock shaft the pawl 108 is disengaged therefrom by the engagement of the tail piece of the pawl with the end of the lever 114 which has previously been returned into the path of the tail piece as presently described. The arm 100, during this return movement of the rock shaft, is returned to its initial position against a stop screw 120 on the frame of the machine by a spring 122 connected with the free end of the arm. This return movement of the arm 100 carries the sliding sleeve 98 therewith, but the rod 96 and cam segments 60 are held in raised position to retain the sole in contact with the pad by the locking device 68—70. The lever 114 which controls the connection between the rock shaft 78 and the arm 100 is actuated through an upright rod 124 having its lower end pivotally connected to the forward end of the lever 114. Upon the depression of the rod by swinging the jack into operative position as hereinafter described, the lever 114 is swung out of engagement with the tail piece of the pawl 108 and when the rod is released by vertical movement of the jack, which occurs prior to said return movement of the rock shaft 78, a spring 126 connected with the rod acts through the rod to return the lever into the path of the tail piece of the pawl, this return movement of the lever being limited by the engagement of a stop screw 127 on the end of an arm thereof with the machine frame.

It will be understood that while the mechanism connecting only one jack with the rock shaft 78 has been described, that there is a separate mechanism of the same construction and mode of operation connecting the other jack with the rock shaft.

The cross-heads 48 for applying sole pressing movements to the jacks are mounted to slide on the central supporting rod 36 (Fig. 1) and the side rods 32, the inner sides of the cross-heads being provided with guideways which engage opposite sides of the central rod 36 and the outer sides of the crossheads being provided with guideways which engage the rods 32. The mechanism for actuating each cross-head is automatically thrown into operation at the completion of the initial movement of the associated jack, and after the cross-head has been raised a predetermined amount, this mechanism is thrown out of operation and the cross-head is held in sole pressing position. This mechanism comprises a toggle 128, the upper end of the upper arm of which is pivotally connected to the cross-head and the lower end of the lower arm is pivotally connected to the frame of the machine. The knee of the toggle is connected by a link 130 with a wrist pin 132 carried by a gear 134, the wrist pin and gear constituting a crank for actuating the toggle. The gear 134 is carried by a shaft 136 journaled in a bearing at the base of the machine, which shaft is driven by the driving shaft 84 of the machine through a pinion 138, carried by the driving shaft, which meshes with the gear 134. Means is provided for connecting the driving shaft 84 with its driving pulley 82 so that at the completion of the initial movement of the jack, the driving shaft will act to drive the shaft 136 180 degrees which will straighten the toggle 128 and thereby raise the cross-head the requisite amount. The driving shaft will then be automatically disconnected from its driving pulley so that the jack will remain in its sole pressing position.

The means for thus connecting the driving shaft to the driving pulley comprises a clutch shifting collar 140 which is splined on a sleeve 142 secured to the driving shaft. Upon shifting the clutch collar 140 rearwardly, clutch members 144 and 146 carried by the sleeve 142 are brought into engage-

ment with friction clutch surfaces 148 and 150 on the hub of the driving pulley. The clutch member 144 is loosely mounted on the sleeve 142 and is connected with the 5 clutch collar 140 by a pair of arms 152 projecting rearwardly from the clutch collar, the ends of which arms are turned inwardly to engage a groove 154 in the clutch member 144. The rearward movement of the 10 clutch collar 140 acts through the arms 152 to bring an internal friction clutch surface on the rear end of the clutch member 144 into engagement with the friction clutch surface 148 on the hub of the driving pulley, whereupon the clutch member 144 is rotated with the driving pulley. The other 15 clutch member 146 carried by the sleeve 142 comprises an expansion clutch ring 156. At the start of the rotation of the clutch member 144, the clutch ring 156 is expanded and firmly clutches the driving shaft to the driving pulley. The means for expanding the clutch ring 156 comprises a lever 158 pivoted at 160 on one end of the clutch ring 20 and having its lower end received by a slot 162 in the clutch member 144. When the clutch member 144 is rotated by engagement with the friction clutch surface 148 on the driving pulley, the lower end of the lever 25 158 is swung to the left (viewing Fig. 10) which causes a cam lug 164 formed on the upper end of the lever to act on the other end of the clutch ring and thereby expand the ring. The clutch ring is mounted upon 30 lugs 168 projecting rearwardly from a flange or spider 170 forming a part of the sleeve 142. The rotation of the clutch member 144 on the sleeve 142 is limited by the engagement of a pin 172 on the clutch member 35 with a slot 174 in the rear end of the clutch sleeve. Upon shifting the clutch collar 140 forward, the clutch member 144 is thereby carried out of engagement with the clutch surface on the driving pulley 40 which, as the clutch member 144 is then free to turn on the sleeve 142, allows a spring 176 having one end connected to the clutch ring lever 158 to swing the lever in the direction to release the cam lug 164 thereon 45 from engagement with the end of the clutch ring 156, thereby operatively disengaging the clutch ring from the clutch member 150. The driving shaft is then immediately brought to rest by the engagement of 50 a friction brake surface 178 on the forward end of the clutch member 140 with a corresponding brake surface 180 on the frame of the machine.

The clutch collar 140 is shifted to cause 55 the clutch members to become engaged and disengaged at the proper times by means of a yoke 182 (Figs. 2 and 4), the ends of which are provided with rolls which engage a groove in the clutch collar. The yoke 182 60 is formed on the forward end of a lever 184

fulcrumed on a vertical pin 186 mounted in brackets on the frame of the machine. The lever 184 is urged in the direction to cause the clutch members to become engaged by means of a coiled spring 188 connected with the lever, and the lever is held in position to maintain the clutch members out of engagement by means of a downwardly sprung 70 pressed lock bolt 190, the lower end of which engages the rear side of a pin 191 projecting from the upper arm of the yoke 182.

At the completion of the initial movement of the jack, the lock bolt 190 is released from the pin 191 to permit the clutch members to become engaged by the action of 80 the spring 188. The lock bolt 190 is released at this time by the upward movement of the arm 100 mounted on the shaft 78 which, as previously described, acts to initially raise the jack. The hub of the arm 100 carries a cam lug 192 which, as the arm approaches the limit of its upward movement, engages a roll 194 mounted on the free end of an arm 196 secured to a rock shaft 198 mounted in the base of the machine. An arm 200 is secured to one end of the rock shaft 198, the free end of which engages the underside of the head of the lock bolt. The engagement of the cam lug 192 with the roll 194 acts 85 through the arms 196 and 200 to raise the lock bolt 190 out of engagement with the pin 191. When the driving shaft is rotated the requisite amount to straighten the toggle that actuates the cross-head, the lock bolt 190 which has been released by the cam lug 192 during the downward return movement 90 of the arm 100 is moved back of the pin 191 and then carried forwardly by means presently described which, through the yoke 182 shifts the clutch members out of engagement 100 and brings the driving shaft to rest. The lock bolt 190 is actuated in this manner by means of a cam lever 202 upon which it is mounted, which lever is fulcrumed on the vertical pin 186. The lever 202 is actuated 105 by a cam surface on the forward face of a cam disk 206 carried by the rear end of the toggle actuating shaft 136, a cam roll 204 on the lever being maintained in engagement 110 with the cam surface by means of a coiled spring 208 connected with the lever 202.

When one jack has been brought to a position of pressure and the machine is stopped as above described, the other cross-head has been brought into its retracted position as indicated in Fig. 1. As clearly shown in Fig. 1, the toggles are so arranged relatively to their actuating crank that as one is straightened, the other is broken which causes the cross-head connected with the toggle which is being broken to be retracted. As this cross-head approaches the limit of its retracting movement, the pawl 70 of the locking device is lifted out of engagement 120 with the ratchet member 68, allowing the 125 130

cam segments 60 to swing rearwardly by gravity which in turn allows the carrier and jack to drop to their initial position on the cross-head. The pawl 70 is thus released 5 from the ratchet member 68 by a lug 210 on the pawl being brought into engagement with the upper end of a releasing lever 211 pivoted at its lower end on a bracket secured to the machine frame. The upper 10 end of the releasing lever 211 is maintained in position by means of a stop screw 212 secured to a lug on the lower end of the lever, which screw is held against the base of the bracket upon which the lever is mounted, by 15 means of a spring 213 engaging an arm 214 on the lower end of the lever.

This descent of the jack and carrier is accomplished without undue jar by the provision of a buffer comprising a coiled spring 20 209 mounted in a socket in the guiding stud 56 on the cross-head, against which spring the shaft 64 of the carrier strikes.

The jack carrier is so constructed that as it reaches the limit of its retracting movement 25 on the cross-head, the jack is caused to be tilted forwardly to permit the work to be changed, and accordingly the upper portion of the jack carrier is pivotally mounted and is free to swing forwardly at this time. 30 To this end the upper portion of the carrier is provided with downwardly extending supporting arms 215, the lower ends of which are fulcrumed upon the ends of the stationary shaft or rod 64 secured to the lower 35 portion of the carrier. During the movement of approach and the retracting movement of the carrier on the cross-head, the jack and the pivoted portion of the carrier are guided in upright position beneath the pad by the engagement of vertical guide 40 bars 216 on the upper ends of the cross-head with slots 218 in the ends of the horizontal bar 46 secured to the top of the carrier. In order that the guide bars 216 and 45 the ends of the horizontal bar 54 may not prevent the carrier from being tilted forwardly at the completion of its retracting movement on the cross-head, the upper sides of the rear walls of the slots in the bar 54 50 are cut away (Fig. 7^a) to permit the bar 54 to clear the lower ends of the guide bars 216 at the limit of the retracting movement of the carrier, allowing the upper portion of the carrier and jack to be tilted forwardly 55 by gravity. This forward movement of the jack is limited by the engagement of the upper portion of the carrier with a stop 220 projecting from the lower portion of the carrier.

In order that the pawl 70 of the locking device for the carrier will be free to engage with the ratchet member 68 during the initial movement of the jack, means is provided for disengaging the pawl from the releasing lever 211 when the jack is tilted forward.

To this end the outer supporting arm 215 of the carrier is provided with a lug 221 projecting down below the pivot shaft 64, which when the jack is tilted forward engages the upper end of the releasing lever 70 and moves it from beneath the lug on the pawl.

The machine is at rest when the jack is thrown out as described, and it is necessary for the jack to be swung back by the operator beneath the sole pressing pad before the machine can again be thrown into operation.

When the jack is returned to operative position beneath the pad, it is automatically 80 locked in place by means of a latch comprising a lug 222, centrally secured to the rear side of the pivoted portion of the carrier, which is engaged by a shoulder formed on the end of an upwardly spring pressed plunger 224 mounted in the upper end of the guiding post or stud 56 secured to the cross-head, inclined surfaces 226 being provided on the ends of the lugs and plunger which cooperate, as the jack is brought into operative position, to depress the plunger and thereby permit its end to snap in front of the lug. The engaging portions of the members of the latch are of sufficient length so that they will remain in engagement during 85 the initial movement of the jack carrier on the cross-head until the ends of the horizontal bar 46 on the top of the carrier are effectively brought into engagement with the guide bars 216 on the cross-head. In order that the members of the latch 222-224 will not engage during the retracting movement of the jack and thereby prevent the jack from being tilted forward at the limit of this movement, a sufficient play is provided 90 between the ends of the guide bars 216 and the slots in the end of the bar 54 so that the jack will start to tilt forward by gravity before the members of the latch will have an opportunity to effectively engage, with the 95 result that the lug 222 will ride over the inclined surface 226 on the end of the plunger. This play between the lower ends of the guide bars 216 and the slots in the ends of the bar 54 is provided for by chamfering 100 off the lower ends of the rear sides of the guide bars as indicated at 227 in Figs. 7 and 7^a.

It will be recalled that the mechanism for imparting the initial movement of approach 105 to the jack is thrown into operation by the depression of one of the rods 124, a rod 124 being associated with each jack and having its upper end located to the rear of the jack carrier. In the illustrated machine the 110 movement of the jack into operative position is utilized to throw the actuating mechanism for the jack into operation. Accordingly means is provided which act to depress the starting rod 124 when the jack is 115 120 125 130

6 moved into operative position. This means comprises an arm 230 projecting rearwardly from the pivoted portion of the jack carrier, the end of which arm, when the jack is 5 swung into operative position engages the upper end of the rod 124 and depresses the rod a sufficient amount to throw the actuating mechanism for the jack into operation. The rod 124 is returned by its spring 126 to 10 its raised position as the jack rises as previously described, and in order that the end of the rod will not be engaged by the end of the arm 230 while the jack is again being retracted, means is provided for holding the 15 jack out of the path of the arm 230 during the retraction of the jack, which means is released when the jack is tilted forward at the end of the retracting movement thereof. To this end a lug 232 is provided on the rear 20 side of the cross-head, which as the cross-head rises cooperates with an inclined surface 234 on the rod to swing the upper end of the rod back out of the path of the arm 230 on the carrier against the action of a 25 spring 236 having one end connected to the rod. The rod is held in this position, by means of a latch 238, until the jack is retracted and tilted forward. This latch comprises a horizontal lever pivoted at 240 on the cross-head (Figs. 5 and 7) and provided with a shoulder 242 on the end thereof which, when the rod 124 is swung back, is 30 snapped by its spring 244 into engagement with the front side of the rod, the shoulder riding on the side of the rod during the actuation of the cross-head. Means is provided so that when the jack is tilted forward at the end of the retracting movement thereof, the latch 238 will be disengaged from the 35 starting rod 124 allowing the rod to be swung inwardly by its spring 236 into position to be again engaged by the arm 230 to repeat the cycle of operations when the jack is returned to operative position. To this 40 end the inner supporting arm 215 of the pivoted portion of the jack carrier is provided with a downwardly extending lug 248 which, when the jack is tilted forwardly, engages an arm 250 on the latch 238 to 45 swing the latch in a direction to release the rod.

50 While it is preferred to employ the specific construction and arrangement of parts illustrated and described, it is to be understood that this construction and arrangement is not essential except so far as specified in the appended claims, and may be changed or modified without departing from the broader features of the invention.

55 The nature and scope of the present invention having been indicated and a machine embodying the several features of the invention in their preferred form having been specifically described, what is claimed 60 is:

1. A sole pressing machine having, in combination, sole pressing members comprising a sole pressing pad and a shoe supporting jack arranged one above the other, power operated means for first raising the 70 lower member to position the sole of a shoe placed on the jack in contact with the pad and shoe, means for then raising the lower member a predetermined distance, and means for locking the lower member against 75 retracting movement at the completion of the initial movement thereof.

2. A sole pressing machine having, in combination, sole pressing members comprising a sole pressing pad and a shoe supporting jack arranged one above the other, means for raising the lower member to position the sole of a shoe placed on the jack in contact with the pad and shoe, and means automatically thrown into operation for 80 then raising the lower member an invariable distance.

3. A sole pressing machine having, in combination, a sole pressing pad, a shoe supporting jack, means thrown into operation by movement of the jack into operative position for imparting a relative movement of approach to the pad and jack to position the sole of a shoe placed on the jack in contact with the pad and shoe, and then to impart a relative movement to the pad and jack through a predetermined distance to apply pressure to the sole.

4. A sole pressing machine having, in combination, co-operating sole pressing members arranged one above the other, power operated means for raising the lower member a distance dependent upon the thickness of the work, and power-operated means for then effecting a sole pressing movement of the 105 lower member, said latter means being controlled by the thickness of the work to regulate the sole pressing movement.

5. A sole pressing machine having, in combination, co-operating sole pressing members, means for moving one of said members toward the other member a distance dependent upon the thickness of the work, and then a predetermined distance to apply pressure to the work, and means automatically 110 thrown in during said initial movement of one of said members to prevent movement of said member in the reverse direction.

6. A sole pressing machine having, in combination, co-operating sole pressing members, a thrust spring for yieldingly holding one of said members, means for moving the other member toward said yieldingly held member a distance dependent upon the thickness of the work, and power-operated means 120 for moving said other member against the action of the spring through a space determined by the thickness of the work to apply pressure to the work.

7. A sole pressing machine having, in com-

- 7
- bination, co-operating sole pressing members, mechanism for moving one of said members toward the other member a distance dependent upon the thickness of the work, means for disconnecting said member from said mechanism, means for preventing movement of said member in the reverse direction when said member and said mechanism are disconnected, and means for moving said member a predetermined distance toward the other member from the position to which it was moved by said mechanism.
8. A sole pressing machine having, in combination, sole pressing members comprising a sole pressing pad and a shoe supporting jack arranged one above the other, automatic means for raising the lower member to position the sole of a shoe placed on the jack in yielding contact with the pad and shoe, and independent means for then raising the lower member a distance which is invariable in successive operations.
9. A sole pressing machine having, in combination, co-operating sole pressing members arranged one above the other, means for raising the lower member a distance dependent upon the thickness of the work, and means automatically thrown into operation for then raising the lower member a distance controlled by the thickness of the work.
10. A sole pressing machine having, in combination, co-operating sole pressing members, means for moving one of said members toward the other a distance dependent upon the thickness of the work and means operating in time relation to said first-mentioned means to move the said one member a predetermined distance in the same direction to apply pressure to the work, and means for positively preventing movement of said movable member in the reverse direction after the completion of the initial movement of said movable member.
11. A sole laying machine having, in combination, a sole laying pad, a shoe supporting jack capable of being moved into and out of operative position, mechanism for relatively actuating the pad and jack to apply pressure to the sole of a shoe placed on the jack, means actuated by movement of the jack into operative position for throwing said mechanism into operation, and means for causing the jack to move into inoperative position after the completion of the effective operation of the jack and pad.
12. A sole pressing machine having, in combination, a sole pressing pad, a shoe supporting jack capable of being moved into and out of operative position, mechanism thrown into operation by movement of the jack into operative position for imparting a relative movement of approach to the pad and jack to position the sole of a shoe placed on the jack in light yielding contact with the pad and shoe, and for then relatively actuating the pad and jack to apply pressure to the sole, and means for causing the jack to move into inoperative position after the completion of the effective operation of the jack and pad.
13. A sole pressing machine having, in combination, a sole pressing pad, a shoe supporting jack capable of being moved into and out of operative position, and mechanism thrown into operation by movement of the jack into operative position for relatively actuating the pad and jack to apply a predetermined pressure to the sole of a shoe placed on the jack regardless of the thickness of the sole.
14. A sole pressing machine having, in combination, a sole pressing pad, a cross-head, a carrier mounted to move on the cross-head, a shoe supporting jack mounted on the carrier, means for actuating the carrier to position the sole of a shoe placed on the jack in contact with the pad and shoe, connections between the carrier and cross-head to prevent movement of the carrier in the reverse direction, and means for actuating the cross-head to cause the pad and jack to apply pressure to the sole.
15. A sole pressing machine having, in combination, a sole pressing pad, a cross-head, a carrier mounted to move on the cross-head toward and from the pad and also mounted to move into and out of alignment with the pad, a shoe supporting jack mounted on the carrier, means for moving the carrier on the cross-head to position the sole of a shoe placed on the jack in contact with the pad and for preventing retracting movement of the carrier, and means for actuating the cross-head to cause the pad and jack to apply pressure to the sole.
16. A sole pressing machine having, in combination, a sole pressing pad, a cross-head, a carrier mounted to move on the cross-head, toward and from the pad, a shoe supporting jack mounted on the carrier, a cam mounted on the cross-head and engaging the carrier, means for actuating the cam to move the carrier on the cross-head so as to position the sole of a shoe placed on the jack in contact with the pad, and means for actuating the cross-head to cause the pad and jack to apply pressure to the sole.
17. A sole pressing machine having, in combination, co-operating sole pressing members, a thrust spring for yieldingly holding one of said members, means for moving the other member towards the yieldingly held member a distance dependent upon the thickness of the work, independent means for moving said other member an invariable distance against the action of said spring to apply pressure to the work, and means for adjusting said spring to vary the pressure applied on the work.

18. A sole pressing machine having, in combination, sole pressing members comprising a sole pressing pad and a shoe supporting jack, automatic means to move one of said members to position the pad and the sole of a shoe placed on the jack in contact and then to move said member a predetermined distance which is invariable in successive operations to apply pressure to the sole, and means for varying the amount of pressure applied to the sole.

19. A sole pressing machine having, in combination, sole pressing members comprising a sole pressing pad and a shoe supporting jack, means for moving one of said members to position the sole of a shoe placed on the jack in contact with the pad and shoe, automatically actuated means for then imparting a sole pressing movement to the pad and jack, the compression due to said movement always increasing as the movement proceeds, and automatic means for arresting the operation of said automatically operated means at a point corresponding to the same point in the compression cycle irrespective of varying characteristics of the work.

20. A sole pressing machine having, in combination, a sole pressing pad, a shoe supporting jack, a driving shaft, and means actuated by the driving shaft for imparting a relative movement of approach to the pad and jack to position the sole of a shoe placed on the jack in contact with the pad and shoe and then impart a sole pressing movement to the pad and jack to apply pressure to the sole, said pressing movement being regulated by the thickness of the work.

21. A sole pressing machine having, in combination, a sole pressing pad, a shoe supporting jack, a driving shaft, and mechanism actuated by the driving shaft for imparting a relative movement of approach to the pad and jack to position the pad and the sole of a shoe placed on the jack in contact and then to impart a sole pressing movement to the pad and jack to apply pressure to the sole, and means for disconnecting the driving shaft and said mechanism, the pressure applied at the instant of disconnection being determined by the thickness of the work.

22. A sole pressing machine having, in combination, a sole pressing pad, a shoe supporting jack, a carrier for the jack, a cam acting on the carrier capable of being rotated to position the sole of a shoe placed on the jack in contact with the pad and capable of then being moved bodily to apply pressure to the sole, and power operated means for imparting said rotary movement to the cam.

23. A sole laying machine having, in combination, a pair of sole laying pads, a pair

of shoe supporting jacks cooperating therewith capable of being moved into and out of operative position, mechanism for relatively actuating the pads and jacks to apply pressure to the soles of shoes placed on the jacks, and means actuated by movement of one of the jacks into operative position for throwing said mechanism into operation while the other jack remains in inoperative position.

24. A sole laying machine having, in combination, a sole laying pad, a shoe supporting jack cooperating therewith capable of being moved into and out of operative position, mechanism for moving the jack toward the pad in a compound measuring and pressing movement to apply pressure to the sole of a shoe placed on the jack, and means actuated by movement of the jack into operative position for throwing said mechanism into operation.

25. A sole pressing machine having, in combination, a sole pressing pad, a shoe supporting jack, means for imparting a relative movement of approach to the pad and jack to position the pad and the sole of a shoe placed on the jack in light yielding contact, and means for then imparting a relative sole pressing movement of invariable extent to the pad and jack to apply pressure to the sole.

26. A sole pressing machine having, in combination, a sole pressing pad, a shoe supporting jack, means thrown into operation by movement of the jack into operative position for imparting a relative movement of approach to the pad and jack to position the sole of a shoe placed on the jack in contact with the pad and shoe, then to impart a relative movement to the pad and jack through a predetermined distance to apply pressure to the sole, and then to return the jack to inoperative position.

27. A sole pressing machine having, in combination, twin sole pressing pads and shoe supporting jacks, means thrown into operation by movement of one of the jacks into operative position for imparting a relative movement of approach to it and its corresponding pad to position the sole of a shoe placed on the jack in contact with the pad and shoe, then to impart a relative movement to the pad and jack through a predetermined distance to apply pressure to the sole and automatically to release the other jack from operative position.

28. A sole pressing machine having, in combination, a sole pressing pad, a shoe supporting jack, means tripped into operation by movement of the jack into operative position for imparting a relative movement of approach to the pad and jack to position the sole of a shoe placed on the jack in contact with the pad and shoe, and then to im-

part a relative movement to the pad and jack through a predetermined distance to apply pressure to the sole, and means for afterward throwing the jack into inoperative position and resetting the trip.

29. A sole pressing machine having, in combination, a sole pressing pad, a shoe supporting jack, means tripped into operation by movement of the jack into operative position for imparting a relative movement of approach to the pad and jack to position the sole of a shoe placed on the jack in contact with the pad and shoe, and then to impart a relative movement to the pad and jack through a predetermined distance to apply pressure to the sole, and power driven

means for afterward throwing the jack into inoperative position and resetting the trip.

30. A sole pressing machine having, in combination, twin sets of sole pressing members comprising a sole-pressing pad and a shoe supporting jack, means for moving one of said members to position the sole of a shoe placed on the jack in contact with the pad and shoe, and mechanism for thereupon imparting a sole pressing movement of predetermined extent to the pad and jack, and to release the pressure between the other said pad and jack, said mechanism being thrown into action by the movement of the said means.

HARRY D. ELLIOTT.
